OFFSET SWITCH BLADE

Frank G. Nicolaus, Chicago, Ill., assignor to
Raymond T. Moloney, Chicago, Ill.

Application August 11, 1955, Serial No. 527,666

6 Claims. (Cl. 200—166)

This invention pertains to switch blades for use in stack switches, and according to which certain offsets are provided which make it possible to stagger sets of the blades while maintaining the operating load in one straight line or columnar relation, so that a relay armature or like actuating instrumentality will be more efficiently loaded, and more blades may be more efficiently utilized in a given assembly than was possible with previous types of blade.

A further object is the provision of switch blades having double-offset ends or tabs for cooperation in sets, the blades being stacked with the offsets alternately in right- and left-hand staggered relation so as to provide important operating clearances and improved loading for the operating instrumentality, e. g. an armature in a relay.

Additional objects and aspects of novelty and utility relate to the construction and operation of the illustrative embodiment described hereinafter in view of the annexed drawing in which:

Fig. 1 is a plan view of a master blade;

Fig. 2 is a plan view of a companion blade;

Fig. 3 is a side elevation of a relay employing the new switch blades;

Fig. 4 is a top plan view of the device of Fig. 3;

Fig. 5 is a front elevation of the relay of Fig. 3;

Fig. 6 is a plan view of a dual insulating wafer for single-screw mounting;

Fig. 7 is a top plan view of a relay with dual-column stack and single-mounting screw;

Fig. 8 is a plan view of a blade punching with dual lugs.

Stack or jack switches employ a form of contact which is a narrow elongated blade of springy, but fairly low-resistance metal, such as Phosphor bronze. These blades are secured at one end in a stack of insulating wafers with their opposite free ends extending into space and being free to flex, the free end regions also usually carrying a contact point or button.

Such contact blades are very commonly used in relays, motor cam switches and the like, and in their simplest form, they consist of only two spring blades, one of which is to be flexed into or out of engagement with the other.

When a stack switch contains a large number of switch blades, it is often referred to as a "pile-up" and it may require an appreciable pull or thrust to flex the sets of blades in a large pile-up, so that a problem arises when a maximum number of contacts must be loaded onto a given or available operating force. Very often several pile-ups are required to be used in one relay, and the relay armature may be required to flex a load equivalent to the mechanical resistance of as many as eighteen blades.

When it is not possible to design the electromagnetic components of a relay to provide satisfactory power for the working load, marginal operation often results, especially in the cheaper styles of relay.

The present invention provides improvements in the switch blade which reduce the total loading by the blades, distribute the load more evenly in multi-stack assem-

2

bles and large pile-ups, and make it possible to eliminate certain protective accessories necessarily used with the conventional type of blade.

In Fig. 1 there is shown what is termed for convenience 5 a master blade 10 which is characterized in that its working end comprises a narrow finger 11 having double or staggered offset end portions 12 and 13.

The offset tab portion 13 lies along a center line or longitudinal axis through the blade, as shown in dash-dot line, and a contact point 14 is fixed, as by staking, in finger 11 close to the juncture with the first offset 12.

The remainder of the contact comprises the stock portion 15, which is of full width (comparable to the width of the old style blades) pierced as at 16 to receive mounting screws 17 (Figs. 3 and 4), and having a pierced tail 18 constituting a soldering lug.

The companion or secondary blade 10A is shown in Fig. 2, and is substantially identical in its stock parts 15A, 16A, 18A, to the master blade; moreover, the finger portion 11A thereof is the same as that in the master blade except for the fact that both offsets and the tab are omitted.

The blades generally indicated at 10 and 10A (Figs. 1 and 2) are used in pairs or triplets each comprising a set, and there may be one or more sets of pairs or triplets in the same column or pile-up.

In the view of Fig. 4, there is shown only one stack or pile-up; but this is subdivided, in a manner of speaking, into two right and left columns X and Y, it being 30 observed however that all of the tabs 13 are disposed in one load line Z which lies in a vertical line which is located in a triangular array relative to the columnar axes X and Y. This is brought out in Fig. 5 where these three lines are shown in their vertical relationships.

35 In mounting the sets of blades, whether pairs or triplets, they are turned right- and left-hand to provide for clearance between sets, and preferably so that there will be equal numbers of blades in the several columns X and Y, with all of the actuating tabs or offsets 13 lying along the one load line Z.

One of the important advantages of the new shape of blade arises from offsetting the sets alternately right- and left-hand when they consist partly or entirely of triplets.

40 In a triplet, the master blade is normally biased and closed with a first or upper one of its two companion blades, both blades being flexed in this condition; and upon actuation the master blade will disengage the first or normal blade, pass through and below a mid-position,

50 and continue on to engage the second or lower blade of this set; the latter action requires some freedom or range for the second blade to yield and flex downwardly from its normal open-circuit condition in order to assure that the electrical contact established between any two blades 55 shall be positive and firm. Thus, in whichever of the two opposite directions the master blade travels, it must have freedom for overtravel. This is true of both pairs and trios.

55 In the old type of pile-up, it was required that there be extra space provided between the various sets of contacts (especially triplets) lying in the same column and, moreover, that there be extra insulation (usually in the form of a strip of fish paper) to cover any blade which might accidentally be touched by another blade in an 60 adjoining set in the actuating movements thereof.

These precautionary requirements commonly meant the expense of extra insulating wafers between sets in the stock or pile, in addition to the fish paper strips, so that extra space and material and labor were needed to prevent short circuits and damage.

The new contacts permit offset columnar or right- and left-hand mounting in alternate sets, so that the danger

of a blade in one set engaging any blade in an adjoining set is eliminated, since the critical portions of the new blades behind the fingers 11 thereof are staggered.

The utility of these clearance features is not restricted to the triplet sets but applies to dual-contact sets also, because the companion or secondary contacts of such pairs must flex measurably upon making contact for reliable results, and clearance for such movement is provided by the new contact means without use of spacers and other expediencies.

The relay construction shown in Fig. 3 is illustrative of the application of the new stack switch to a conventional and simple type of relay in which the armature 30 is provided with an insulated actuating panel 31, having a series of horizontal blade slots 32 (Fig. 5) adapted to receive the free end portions of contact blades, and through which (Fig. 4) the actuating tabs 13 of the new type blades project.

At the rear of this relay (Figs. 3 and 4) is a flange 33 having a plurality of sets of tapped holes 34, 35, 36 to receive the switch-mounting screws 17.

In the embodiment of Fig. 4, only one stack switch is shown, and this is mounted centrally at holes 36 so that the tabs 13 are located centrally of the armature panel 31. If two similar switches were desired, they would preferably be mounted at the pairs of holes 34 and 36, so as to present a balanced loading on the armature. The novel construction is not limited to use in any particular type of relay, but is generally applicable to any situation where a stack switch would be used.

Switch blades with offset contacts have been used heretofore in telephone relays of the type where the contacts are not favorably situated for direct engagement with the actuating levers; but these arrangements did not provide the construction nor operation of the improvements disclosed herein with respect to loading the actuating armature or reducing space as well as material and other manufacturing costs.

Because dummy spaces are not needed to provide clearance between sets of the new type blades (of which at least one is a trio) in the same column, it is possible to utilize one insulating wafer which is common to two columns or stacks. A dual wafer 40 of this type is depicted in Fig. 6, and includes four holes 42 for the blade sleeves and only one central hole 41 to receive a single mounting screw 45 (Fig. 7). Thus one screw instead of four is required to mount the stack, so that savings are effected both in materials and in assembly cost, the operations in assembling the wafers to build up a stack being an especially significant item of cost.

In Fig. 8 there is shown a punched blade 50 having right and left lugs 51, 52, either of which may be sheared off to provide the alternately located lugs for each pair of coacting blades, so that two sets of dies are not needed.

I claim:

1. In a switch, at least two elongated metal blades respectively secured at one end one above the other to extend in parallelism in the same direction, each blade having a longitudinally-extensive finger portion projecting freely along opposite sides of a common axis parallel thereto, one of said blades having its free end offset toward said axis and again offset on said axis to extend a substantial distance along the latter and define an axially-extensive and aligned actuating tab.

2. In a stack switch, cooperative elongated blades in sets each blade having a stock part at one end adapted for mounting in the stack, and each blade having a narrowed finger portion extending from the appertaining stock part and offset a substantial distance at one side of a longitudinal axis through the middle of the stock part, at least one blade in each set having an end portion with a double offset projecting first toward said axis and then into a terminal tab portion in alignment with said axis, all offsets being kept within a line extended along

the outermost margins of said stock part paralleling said axis.

3. The blade structure defined in claim 2 further characterized in that said sets of blades are made right- and left-hand and are disposed in the stack on opposite sides of said axis such that all said tabs for a given switch stack lie in one load column.

4. In a jack switch, elongated spring contact blades in sets each blade having a mounting end and a free end portion and having the respective mounting end portions thereof arranged in a pile-up in a stack of insulating wafers with the blades of each set extending one above another in the direction of their longitudinal axes, the free end portions of each blade including a substantially longitudinally-extensive finger portion which lies on one side of the appertaining longitudinal axis, at least one blade in each set having said finger portion offset near the free end thereof toward said axis with a terminal tab extending in the direction of and along said axis, certain of said blades being of opposite hand and the finger portions of certain of said sets lying in a first column on one side of said axis while the finger portions of other sets lie in a second column on the opposite side of said axis such that the blade fingers in the first column may flex without engaging the blade fingers of the second column, the tab portions of all sets lying one above another in a third column along a common load axis for joint actuation by an operating instrumentality engageable therewith.

5. A construction according to claim 4 further characterized in that there are a plurality of said pile-ups in a single stack of said wafers and at least two sets of not less than two cooperating blade contacts in each said set and the tab portions of the sets in each said pile-up lie in respectively different but parallel load axes for joint engagement and movement by an actuating instrumentality movable in the general direction of said load axes.

6. Switch blades in sets for use in stack switches, each set including at least one right-hand and one left-hand blade, said blade set comprising: a pair of elongated, flat strips of conductive springy metal respectively constituting a right- and a left-hand blade of a set, and each blade having at one end a wide mounting portion 15 or 15A which is substantially symmetrically disposed on opposite sides of a long axis extending through the middle of the blade along the length thereof, the mounting portion of each blade having a narrowed, longitudinally-extensive finger portion 11 or 11A, the major part of which lies on only one side of said axis in the direction crosswise of the blade, the free end portion of one of said fingers having a double offset including an intervening portion 12 directed angularly back toward said axis, and a terminal tab portion 13 extending from said intervening portion a short distance in a direction along said axis, said blades being adapted for mounting one spaced above another in a switch stack engaging said mounting portions thereof, with said finger portions thereof projecting into space to flex away from said axis in a direction normal to their mounting planes, the finger portions of each blade of the set lying at a side of said axis which is opposite from the other crosswise of the width of the blades with said terminal tab portion of one blade projecting beyond the free end of the finger of the companion blade for engagement with an operating instrumentality, said blades each having contact means situated thereon along said axis in confronting relation at a point which is inward of the location of said double offset.
